UNITED STATES PATENT OFFICE

2,064,897

MANUFACTURE OF ARTIFICIAL SILK

Paul Esselmann, Wolfen Kreis Bitterfeld, Germany, assignor to I. G. Farbenindustrie Aktiengesellschaft, Frankfort-on-the-Main, Germany

Application July 26, 1934, Serial No. 737,121
In Germany July 28, 1933

3 Claims. (Cl. 117—2)

My present invention relates to the manufacture of artificial silk and more particularly to an improvement in the manufacture of artificial silk according to the bobbin spinning system.

5 One of its objects is an improvement in the manufacture of artificial silk according to the bobbin spinning system which is efficient and which avoids certain drawbacks involved with the bobbin spinning process as hitherto in use.

10 Further objects will be seen from the detailed specification following hereafter.

Reference is made to the accompanying drawing in which Figs. 1, 2 and 3 illustrate the process according to this invention.

15 Fig. 1 shows twisting in a centrifugal box according to this invention;

Fig. 2 shows a side view of an arrangement for spinning on a plate rotating about its axis and simultaneously performing a reciprocating movement, and

20 Fig. 3 shows a front view of the arrangement shown in Fig. 2.

According to this invention the de-acidified and dried, or de-acidified, after treated and dried, viscose artificial silk wound on bobbins is not 25 twisted on twisting spools as usual, but, while it is twisted, is brought into the form of a winding, in which operation there are used an ordinary twisting spindle and for receiving the threads a reciprocating plate or a centrifuge 30 box.

Such rotating and changing devices for winding the twisted thread are described, for example, in German Patent No. 169,906 or British Patent 35 No. 414,991. If the silk on the spool is only de-acidified and dried, the after-treatment is applied after the twisting process to the centrifuge cakes or to the shapeless windings produced on the plates. The windings produced by the above- 40 mentioned mode of operation can forthwith be improved or they can be put directly on the market and supplied to the consumer.

The process of the invention renders it possible 45 to produce marketable windings of great length of thread by a shortened and cheaper process. The twisting process is essentially simpler and does not require the same great attention as does the known stage or ring-twisting machine. It is of essential importance that the silk should 50 be moistened before it is received in the form of a cake or shapeless winding. By this means, particularly in the case of completely after-treated and dried spool silk, the inner tensions of the thread are again completely compensated 55 so that the silk can subsequently be ready for

any sphere of application in the industry. The same applies to the merely de-acidified silk which is subsequently after-treated until finished in the form of a winding or a cake and also dried while avoiding any tension.

5 The following examples illustrate the invention:

Example 1.—Artificial silk made from viscose which, in the spinning process is wound on spools, is freed from sulfur on these spools by 10 means of a suction-washing treatment, after-treated until finished, and dried. From the rapidly rotating spool placed on a twisting spindle the dried silk is drawn off overhead or by unrolling over a roller or a draft device consisting 15 of a number of rollers, is thoroughly wetted on or behind this drawing-off member by means of a wet sponge or a thread guide which is kept wet, and is deposited on a plate disc which is driven by planet gearing. The winding thus formed 20 can, after drying, be used directly on the manufacturing machines. With this object in view it may be deposited on a suitable plate having a conical retaining device.

Alternatively, the viscose artificial silk may be 25 de-acidified and dried on the spinning spool and then twisted in the manner described and deposited on a plate disc in the form of a winding. In this case the entire after-treatment is applied only to the finished winding. The known methods 30 in which the windings are either irrigated or cleaned by means of sucking or forcing the treating liquid through them, may be adopted. Furthermore, in this case, the windings are advantageously either bound underneath with threads 35 or are covered with permeable cloths, in order that they may be protected as much as possible during treatment.

Example 2.—Viscose artificial silk spun on a spool is de-acidified in known manner, after- 40 treated until finished and dried. The thread is then withdrawn overhead from the spool or unrolled, and twisted in a centrifugal box. After it has passed the removing device, which may consist of a roller or a number of rollers, the 45 thread is thoroughly wetted with water or soap solution. The box of the centrifuge is preferably made of light material, for example of perforated sheet aluminium, and can be built in an ordinary twisting machine, and driven by a belt. 50 Its diameter may be such that within the cake of thread produced there is room for the insertion of a thick conical pin, which is transferred, with the cake on it, to the manufacturing machine. When spinning spools are used which are 55

only de-acidified but not freed from sulfur, the cake produced in the centrifugal box is subsequently subjected to the usual cleaning process according to one of the known methods.

5. What I claim is:

1. In the manufacture of artificial silk according to the bobbin spinning system wherein spun thread is wound on a bobbin, deacidified and dried, the improvement which comprises drawing the dry thread off the bobbin by passing the same over a draft device, simultaneously rotating the bobbin at a sufficient speed to impart twist to the thread, wetting the twisted thread and imparting additional twist to the wetted thread while collecting the same in the form of an unsupported winding or cake.
10. 2. In the manufacture of artificial silk according to the bobbin spinning system wherein spun thread is wound on a bobbin, deacidified and dried, the improvement which comprises drawing the dry thread off the bobbin by passing
15. 3. In the manufacture of artificial silk according to the bobbin spinning system wherein spun thread is wound on a bobbin, deacidified and dried, the improvement which comprises drawing the dry thread off the bobbin by passing the same over a draft device, simultaneously rotating the bobbin at a sufficient speed to impart twist to the thread, wetting the twisted thread and forwarding the wetted thread to a centrifugal box whereby the thread is given additional twist and is collected in the form of an unsupported winding or cake.

PAUL ESSELMANN. 20
